UNITED STATES PATENT OFFICE

113,559

DESIGN FOR A CIGARETTE BOX OR SIMILAR ARTICLE

Lurelle Guild, Norton, Conn., assignor to Kensington, Incorporated, New Kensington, Pa., a corporation of Pennsylvania

Application April 13, 1938, Serial No. 76,459

Term of patent 3½ years

To all whom it may concern:

Be it known that I, Lurelle Guild, a citizen of the United States, residing at Noroton, in the county of Fairfield and State of Connecticut, have invented a new, original, and ornamental Design for a Cigarette Box or Similar Article, of which the following is a specification, reference being had to the accompanying drawing, forming a part thereof.

Fig. 1 is a top plan view, Fig. 2 is a side elevation, and Fig. 3 is an end elevation of a cigarette box or similar article embodying my new design.

I claim:

The ornamental design for a cigarette box or similar article, as shown.

LURELLE GUILD.
